[57] ABSTRACT

An electric analog calculating circuit uses a single logarithmic stage for all steps of a calculation. Each input quantity is applied to the stage and the resulting output stored in a signal storage device. The stored quantities are then combined in the required manner and the logarithmic stage is used in the negative feedback path of a comparator to provide the required output quantity.

ELECTRIC ANALOGUE CALCULATING CIRCUITS

This invention relates to electric analogue calculating circuits, and in particular to such circuits having logarithmic characteristics.

Logarithms are commonly used in mathematical operations to simplify the procedure, and electric circuits have been developed to take advantage of the logarithmic characteristics of certain circuit elements, such as the diode. One of the simplest mathematical operations employing logarithmic techniques is the multiplication of two quantities. Such an operation requires the separate derivation of the logarithm of each quantity, the summing of these two logarithms, and the determination of the antilogarithm of this sum. Conventional circuits employ separate logarithmic elements for each of the stages of this calculation, and this gives rise to a serious problem. Diodes, which are normally used as logarithmic circuit elements, are temperature-sensitive, and the use of three such devices may lead to serious inaccuracies unless complex and costly precautions are taken to maintain all three at the same temperature.

It is an object of the invention to provide an electric analogue calculating circuit for performing logarithmic operations in which the problem of thermal instability is considerably reduced.

According to the present invention there is provided an electric analogue calculating circuit which includes a logarithmic stage arranged to produce an output signal proportional to the logarithm of an input signal, N signal storage devices, a high-gain differential amplifier, and switchable interconnections to allow the output from the logarithmic stage in response to N successive input signals to be stored in the N signal storage devices respectively and thereafter to apply the sum of the stored signals in relative senses predetermined in accordance with the nature of the calculation as one input to said amplifier whilst applying the output from the amplifier in a negative feedback sense to its other input by way of the logarithmic stage, whereby the output from the amplifier represents the result of the calculation.

The invention will now be described with reference to the accompanying drawings, in which:

FIG. 1 is a schematic circuit diagram of a circuit for multiplying together two quantities;

FIG. 2 to 5 illustrate the operation of the circuit of FIG. 1; and

FIGS. 6 and 7 illustrate other applications of the invention.

Referring now to FIG. 1, the basic circuit comprises two differential amplifiers A1 and A2, a circuit element providing a logarithmic characteristic, three storage capacitors and six ganged four-position switches. A stage 10 having a logarithmic characteristic is provided by a differential amplifier A1 having its non-inverting input earthed and with the collector-base diode of a transistor TL connected between its output and its inverting input. The base of the transistor is connected to earth potential. Also connected to the inverting input is one end of an input resistor R, the other end of which is connected to the moving contact of a four-position switch S1. Positions 1, 2 and 3 of this switch are for connection respectively to a reference voltage V_R and to input voltages V_1 and V_2 , whilst the fourth position is not connected.

The output of amplifier A1, besides being connected to the emitter of transistor TL, is connected to the moving contacts of switches S2 and S3. Only the fourth position of S2 is used, being connected to the non-inverting input of a second high-gain differential amplifier A2. The first two positions of switch S3 are connected together and to the junction between two signal storage devices in the form of capacitors C1 and C3. The other side of capacitor C3 is connected to the inverting input of amplifier A2, whilst the other side of capacitor C1 is connected through a further signal storage device in the form of a capacitor C2 to earth potential. The third position of switch S3 is connected to the junction between capacitors C1 and C2. A fourth switch S4 has its moving contact earthed, and positions 1 and 2 are connected together to the junction between C1 and C2.

The non-inverting input of amplifier A2 is also connected to the moving contact of a switch S5, having positions 1, 2 and 3 earthed and position 4 not connected. The output of amplifier A2 is connected to the moving contact of the last switch S6. Position 1 of this switch is connected to the inverting input of the amplifier, whilst position 4 is connected to an output terminal and to the moving contact of switch S1.

The operation of the circuit of FIG. 1 will now be described with reference to FIGS. 2 to 5, each of which is a schematic circuit diagram showing the circuit connection at each stage of its operation.

It is necessary initially to apply a reference voltage V_R to the input of the logarithmic stage to establish a datum, since the logarithm of zero is an indeterminate quantity. FIG. 2 shows the circuit arrangement for this stage of the operation. The voltage V_R is applied to the input of the logarithmic stage, the output of which is applied to capacitors C1 and C3. The output of amplifier A2 is connected to its inverting input, thereby acting in a negative feedback manner to maintain the adjacent plate of capacitor C3 at virtual earth, and the non-inverting input is earthed. In this condition the output voltage of A1, representing the quantity $\log_e V_R$ is stored on both capacitors, the two common ends having the same polarity.

When the switches are moved to position 2, the first input voltage V_1 is applied, and the connection between output and input of amplifier A2 is broken. Otherwise the circuit arrangement is unchanged, as shown in FIG. 3. The new input voltage gives rise to a new output voltage from the logarithmic stage 10, representing $\log_e V_1$ and this is stored on capacitor C1, regardless of the voltage previously stored there leaving capacitor C3 holding $\log_e V_R$.

Position 3 of the switches causes the second input voltage V_2 to be applied to the input of the logarithmic stage 10, and the switches S3 and S4 ensure that the output of the stage, representing $\log_e V_2$, is stored by capacitor C2 as shown in FIG. 4 with capacitors C3 and C1 maintaining their respective charges.

When the switches are moved to the fourth position the circuit arrangement changes considerably, as FIG. 5 shows. The output of the logarithmic stage 10 is now applied directly to the non-inverting input of amplifier A2, whilst the three capacitors C1, C2 and C3 are connected in series between earth and the inverting input. The output of A2 is connected to the output terminal and to the resistor R to form the input to the logarithmic stage. Hence the logarithmic stage 10 forms the

feedback element in the negative-feedback path of amplifier A2.

The three voltages stored on the capacitors C1, C2 and C3 represent respectively $\log_e V_1$, $\log_e V_2$ and $\log_e V_R$, the last-mentioned being of opposite polarity to the other two. Hence the voltage applied to the inverting input of A2 represents $(\log_e V_1 + \log_e V_2 - \log_e V_R)$, that is $\log_e(V_1 \cdot V_2 / V_R)$. Amplifier A2 operates in such a manner as to maintain its two inputs equal to one another, and hence the output of A2 becomes such that the voltage applied to its non-inverting input also represents $\log_e(V_1 \cdot V_2 / V_R)$. However, this input voltage applied to the non-inverting input of A2 is itself the output of the logarithmic stage. Hence the input to the logarithmic stage, which is equal to the output of the amplifier A2, must represent the function $V_1 \cdot V_2 / V_R$.

The reference voltage may conveniently be used as a scale factor in the operation of this circuit. Thus a value of V_R of one volt effectively results in an output equal to the product of the two inputs. Similarly, if the inputs V_1 and V_2 are large, the reference voltage may also be made larger to provide the necessary scale factor.

Each step in the operation of the circuit as described above produces an offset voltage due to the operation of the logarithmic stage. Hence the expressions for output and input voltages given above are simplifications. However, the final step in the operation will result in the cancellation of these offset voltages since the two inputs of amplifier A2 are maintained at the same potential.

In order to produce the circuit described above in practical form it is necessary to arrange for the switches to be moved sequentially from one position to another. In practice mechanical switches will probably not be used; semiconductor switches controlled by suitable timing waveforms are more suitable.

The circuit described above has several advantages over known circuits. The main advantage is that a single logarithmic element is used which is time-shared between the various functions which it has to perform. Thus if the switching is carried out at a suitable speed the question of temperature sensitivity will probably not arise. In addition, the circuit is such that the offset voltages are automatically taken care of, so that output errors do not result from this source.

The basic arrangement of FIG. 1 may be modified in order to perform mathematical operations other than multiplication. FIG. 6, for example, shows the modifications which are necessary to enable the circuit of FIG. 1 to perform division. This requires alteration of some of the connections to switches S3 and S4, and the addition of a further four-position switch S7 between capacitor C2 and earth potential. As will be seen from FIG. 6, position 3 of switch S3 is no longer connected to the junction of C1 and C2, but is now connected to the "bottom" end of C2. Position 3 of switch S4 is connected to the junction of C1 and C2, as are positions 1 and 2. The extra switch is arranged to connect the "bottom" end of C2 to earth when all the switches are in position 4. The operation of the circuit is very similar to that of FIG. 1, the circuit arrangement with the switches in positions 1 and 2 being as described with

reference to FIGS. 2 and 3. With the switches in position 3, however, capacitor C2 is connected to the output of the logarithmic stage with the opposite polarity, so that with the switches in position 4 the voltage stored on C2 is subtracted from that stored on C1. This is the requirement for the output to represent the division of one input quantity by the other.

The circuit may also be modified to determine fractional powers, such as square roots. FIG. 7 shows the arrangement, which is that of FIG. 1 apart from the addition of a potentiometer VR between the output of the logarithmic stage 10 and switch S3. The potentiometer is used to apply to the capacitors C1, C2 and C3 a desired fraction of the output from the logarithmic stage 10. Hence, for example, if the potentiometer is set to apply to the capacitors only half of the output voltage from stage 10, then the input to A2 with the switches in position 4 would be $(\frac{1}{2}\log_e V_1 + \frac{1}{2}\log_e V_2 - \frac{1}{2}\log_e V_R)$, that is $\frac{1}{2}\log_e(V_1 \cdot V_2 / V_R)$ or $\log_e(V_1 \cdot V_2 / V_R)^{\frac{1}{2}}$. Hence the output would be the square root of the product of V_1 and V_2 , allowing for the scale factor V_R .

The circuit may be modified to perform many other mathematical operations without departing from the essence of the invention, and with the advantages already referred to.

What I claim is:-

1. An electric analogue calculating circuit operable to perform calculations involving a number of quantities each represented by a discrete input signal, which 30 includes a logarithmic stage arranged to produce an output signal proportional to the logarithm of an input signal, a plurality of signal storage devices equal to the number of discrete input signals, a high-gain differential amplifier, and switching means operable to apply 35 the input signals to the logarithmic stage one at a time in a predetermined sequence and simultaneously to connect the output of the logarithmic stage to selected ones of the signal storage devices in a predetermined sequence, and thereafter to interconnect the signal storage devices in predetermined senses to one another and to one input of the differential amplifier whilst applying the output from the amplifier in a negative-feedback sense to its other input by way of the logarithmic stage, the output of the amplifier at this time representing the result of the calculation.

2. A circuit as claimed in claim 1 having three signal storage devices wherein the switching means includes a switching device having four positions in three of which the output from the logarithmic stage is connected to the three signal storage devices respectively, and in the fourth position of which the signal storage devices are connected in series in said predetermined senses to said one input of the amplifier.

3. A circuit as claimed in claim 2 in which the switching device comprises a plurality of separate semiconductor switching elements.

4. A circuit as claimed in claim 1 in which each signal storage device is a capacitor.

5. A circuit as claimed in claim 1 in which the logarithmic stage comprises a differential amplifier having a semiconductor device connected between its output terminal and one input terminal.
